FRANK H. SCHWERIN, OF BELLEVUE BOROUGH, PENNSYLVANIA, ASSIGNOR TO THE DUFF-NORTON MANUFACTURING COMPANY, OF PITTSBURGH, PENNSYLVANIA, A CORPORATION OF PENNSYLVANIA

MOTOR-OPERATED JACK

Application filed November 5, 1926. Serial No. 146,293.

This invention relates to motor-operated, portable, screw lifting jacks, and more particularly to a jack having an air motor; and the object is to provide a compact and efficient construction having the motor incorporated with the jack, and further to provide a rigid and virtually integral structure which can nevertheless be separated into a jack unit and a motor unit, for ready replacement and repair, and further to provide in such a construction that the motor chamber and the interior of the jack and gearing chamber shall be housed and sealed each against the other, in such manner that each will retain its own supply of special lubricant.

In the accompanying drawing forming part hereof:

Fig. 1 is an elevation of the jack, with parts broken away and in section; and

Fig. 2 is an elevation looking at right angles to Fig. 1, with other portions broken away and in section.

The jack has an enclosed frame or housing 2 comprising an enlarged lower portion or base 3, and a standard portion 4. The bottom 5 of this housing, which rests upon the ground, is preferably screwed into the shell constituting the remainder of the base and the standard. A lifting member 6 is guided 25 in the upper part of the standard and has a nut 7 in its lower portion, while a lifting screw 8 is supported rotatably on the bottom of the jack on a bearing 9 and extends upward through the nut into the interior of 30 the lifting member.

A worm-wheel 10 is splined on the hub 11 on the lower end of the lifting screw, and this wheel is meshed by a worm 12 lying in a closed-top chamber 13 of the basal portion 40 of the jack housing. The shaft 14 on which the worm is formed is journaled in bearings 15, 16 in said housing portion, and beyond the internal bearing 16 the basal housing is formed into a chamber 17 for a spur gear 18, 45 which is fixed to this end of the worm shaft.

This chamber is open at the top, or would be if it were not covered by a complementary chamber to be described.

The top of the basal portion of the main jack housing which contains the worm chamber 13 and the gear chamber 17 is formed with a flat ledged seat 19, on which is planted the corresponding basal flange 20 of the housing 21 of a motor and gearing unit 22. Bolts 23 passing through these meeting portions secure the units rigidly together, while a key pin 24 accurately fitting complementary recesses at the end of the meeting portions where the gear 18 is housed insures the proper engagement of this gear 18 with a pinion 25.

The motor is specifically an air motor of the cylinder and piston type having its crank-shaft 26 at the bottom, and is placed directly over the worm chamber, with its shaft parallel with the worm. The housing of the enclosed motor has an annex 27 which may be made of a separate piece from the housing of the motor but firmly bolted thereto. Whereas the motor housing has closed bottom and side walls, this annex chamber has an open bottom to fit the open top of the gear chamber 17 of the main jack housing. A vertical wall 28 back of the gearing in the annex 27, together with a packing 29 in this wall where the crank-shaft passes through it, seal the motor chamber from the gear chambers. The construction is such that the motor will retain the light oil in which it works, while the gear and jack chambers may be supplied with and will retain heavy oil or grease, the different lubricants being kept from mingling.

The crank-shaft 26 has a ball-bearing 30 in the wall 28 and extends across the annex chamber into a roller-bearing 31 in the end 85 wall of that chamber. The pinion 25, which meshes with the gear 18 is fixed on a driven member 32, which is rotatably supported on the crank-shaft extension and in the roller bearing 31. The said member 32 has formed 90

with it the disc 33 carrying the traveling pinions 34 of a planetary gear, the internal gear track 35 of this gearing being bolted fast in the upper housing, while the center pinion 36 is fixed on the motor shaft. The pinion 25 is thus driven at greatly reduced speed and increased force, the force advantage being further increased through the pinion 25 and gear 18 and the worm and worm-wheel 12 and 10, to the screw and nut 8 and 7.

The motor drives the mechanism in both raising and lowering, either the worm or the screw, or both, being of self-holding pitch, and a valve 37 of known kind being provided for controlling and reversing the motor. 38 is the air supply hose.

The construction results in a compact and powerful motor-driven jack in which the jack and its driving motor and gearing are embodied in one portable, operative unit, this unit, however, being readily separable into two units or sections on the plane of cleavage lying between the horizontal shafts, one unit comprising the motor with part of the gearing, and the other unit comprising the jack parts with the remainder of the gearing. If either unit becomes damaged or requires attention it can be set aside or returned to the factory, and can be replaced by another similar unit.

I claim:

1. A jack comprising a housing frame forming a base and standard, the latter provided with a nut, a lifting member, a lifting screw coacting with said nut, a worm-wheel on the lower portion of said screw, a worm meshing said worm-wheel, an air motor mounted on the base of the jack directly over said worm and having a horizontal crank-shaft parallel with the worm, power-multiplying gearing between said crank-shaft and the worm shaft, the motor and gearing having a housing joining with the main jack housing, the motor with part of said gearing, on the one hand, and the remainder of the jack, including the worm wheel and worm and the remainder of said gearing, on the other hand, being separable as units on a plane of cleavage cutting the housing between said horizontal shafts, and means rigidly uniting said units together.

2. A jack comprising a housing frame forming a base and standard, the latter provided with a nut, a lifting member, a lifting screw coacting with said nut, a worm-wheel on the lower portion of said screw, a worm meshing said worm-wheel, an air motor mounted on the base of the jack directly over said worm and having a horizontal crank-shaft parallel with the worm, power-multiplying gearing between said crank-shaft and the worm shaft, the motor and gearing having a housing joining with the main jack housing and the motor chamber being sealed

from the gearing and jack chambers, the motor with part of said gearing, on the one hand, and the remainder of the jack, including the worm wheel and worm and the remainder of said gearing, on the other hand, being separable as units on a plane of cleavage cutting the housing between said horizontal shafts, and means rigidly uniting said units together.

3. A jack comprising a housing frame forming a base and standard, the latter provided with a nut, a lifting member, a lifting screw coacting with said nut, a worm-wheel on the lower portion of said screw, a horizontal shaft in said base carrying a worm meshing said worm-wheel, a gear on the shaft of said worm, a motor mounted on the base of the jack directly over said worm and having a horizontal shaft parallel with the worm, a driven member coaxial with the motor shaft and having a pinion meshing the gear on the worm shaft, a planetary gearing between the motor shaft and said driven member, the motor with said driven member and planetary gearing, on the one hand, and the remainder of the jack, including the worm wheel and worm and the gear on the worm shaft, on the other hand, being separable as units on a plane of cleavage lying between the horizontal shafts, and means rigidly uniting said units together.

4. A jack comprising a housing frame forming a base and standard, the latter provided with a nut, a lifting member, a lifting screw coacting with said nut, a worm-wheel on the lower portion of said screw, a worm meshing said worm-wheel, an air motor mounted on the base of the jack directly over said worm and having a horizontal crank-shaft parallel with the worm, power-multiplying gearing between said crank-shaft and the worm shaft, the motor and gearing having a housing joining with the main jack housing, walls enclosing and sealing the motor chamber from the gearing and jack chambers, the motor with part of said gearing, on the one hand, and the remainder of the jack, including the worm wheel and worm and the remainder of said gearing, on the other hand, being separable as units on a plane of cleavage cutting the housing between said horizontal shafts, and means rigidly uniting said units together.

5. A jack comprising a housing frame forming a base and standard, the latter provided with a nut, a lifting member, a lifting screw coacting with said nut, a worm-wheel on the lower portion of said screw, a worm meshing said worm-wheel, the base portion of the jack housing containing spaced bearings for the worm shaft, a closed worm chamber between said bearings and an open top gear chamber outside of one of said bearings, a gear on the end of the worm shaft in said gear chamber, a housed motor unit mounted

on said base portion of the jack housing, said motor unit having a closed motor chamber over the worm chamber and a gearing chamber annex open at the bottom to fit the gear chamber of the base, power-multiplying gearing in said gearing chamber annex between the motor shaft and said gear on the worm shaft, and means rigidly and separably uniting the housing of the motor unit and its
5 gearing chamber annex to the housing of the base.
